UNITED STATES PATENT OFFICE.

EDWIN BALL STIMPSON, OF BROOKLYN, NEW YORK.

DESIGN FOR A GROMET.

50,433.

Specification for Design.

Patented Mar. 6, 1917.

Application filed June 8, 1914. Serial No. 843,885. Term of patent 3½ years.

To all whom it may concern:

Be it known that I, EDWIN B. STIMPSON, a citizen of the United States, residing at Brooklyn, in the county of Kings and State of New York, have invented a new, original, and ornamental Design for Gromets, of which the following is a specification, reference being had to the accompanying drawing, forming part thereof.

In the drawing, Figure 1 is a perspective

view of a gromet, showing my invention; Fig. 2 is a side elevation of the same.

I claim:

The ornamental design for a gromet, as shown.

EDWIN BALL STIMPSON.

Witnesses:

HELEN V. FITZPATRICK,
MARY H. LEWIS.
